LOW-PRESSURE GASEOUS DISCHARGE LAMP
WITH INTERNALLY MOUNTED RECOMBINATION STRUCTURE

Vernon L. Plagge, East Orange, N.J., assignor to Westinghouse Electric Corporation, East Pittsburgh, Pa., a corporation of Pennsylvania

Filed Mar. 22, 1962, Ser. No. 181,592
11 Claims. (Cl. 313—109)

This invention relates to electric discharge devices and, more particularly, to fluorescent lamps and means for mounting an elongated member therein.

It has recently been discovered that the loading per unit length, and hence the light output, of low-pressure gaseous discharge devices such as fluorescent lamps and the like can be increased without decreasing their efficiency by providing a region within the discharge where electrons and positive ions can recombine. It has also been found that such a region can be established by placing an elongated member within the discharge space which provides a surface at which the desired recombination will occur. The loss of electrons and ions through the recombination process decreases the diffusion length of the discharge and increases the electron temperature which, in turn, increases the loading per unit of lamp length without causing an attendant decrease in efficiency.

Experience has shown that the thickness of the elongated member must be kept very small compared to its surface area, otherwise the free passage of the discharge through the lamp will be obstructed and the current density per unit of cross-sectional area will be increased. When this occurs both the electron temperature and the lamp efficiency decrease.

Preferably, a slender glass rod is mounted within the lamp between the electrodes and in substantial alignment with the envelope axis. The rod is thus suspended in the center of the discharge and provides a recombination surface in the region where the electron and ion concentration is greatest resulting in an optimum increase in the electron temperature and the lamp loading. An "axial rod" highly-loaded fluorescent lamp designed in accordance with these principles is disclosed and claimed in copending U.S. application Serial No. 112,071 of D. A. Larson and P. J. Walsh, filed May 23, 1961, and owned by the assignee of the present invention.

The manufacture of such axial-rod fluorescent lamps has presented a structural problem in that it is difficult to suspend the rod within the envelope without obstructing the discharge path. Mounting the rod in the proper position within the envelope and in a manner such that it will withstand the mechanical shocks encountered during handling and shipping of the lamps further complicates the problem.

With the foregoing in mind, it is the general object of this invention to provide an electric discharge device that contains an elongated member disposed to increase its output but which avoids the manufacturing difficulties and other problems heretofore associated with the use of such members.

Another and more specific object is the provision of a highly-loaded fluorescent lamp that operates on the aforementioned "recombination" principle and can be handled and shipped in the regular manner without being damaged.

Briefly, the aforesaid objects and other advantages are achieved in accordance with this invention by supporting the glass rod within the envelope by means of vitreous struts that are sealed to the inner surface of the envelope. In the preferred embodiment, a plurality of glass rods are mounted in end-to-end relationship within the envelope by bending the ends of the rods to form the

struts, and then sealing these struts to the envelope wall.

Alternatively, a single rod of sufficient length is suspended within the envelope and the discharge space by means of a plurality of spaced struts of vitreous material that are sealed to the inner surface of the envelope and joined to the rod.

In each case, the unsupported lengths of the rod or rods are such that they will withstand the impacts and vibration normally encountered during shipping and handling. A very convenient method for sealing the supporting struts to the inner wall of the envelope from a position located outside the envelope is also provided.

A better understanding of the invention will be obtained by referring to the accompanying drawing, wherein:

FIGURE 1 is an elevational view of a highly-loaded fluorescent lamp incorporating the rod structure of this invention, portions of the envelope being removed to afford a clearer view of the lamp interior;

FIGURE 2 is an enlarged sectional view of a portion of the lamp shown in FIGURE 1;

FIGURE 3 is an elevational view of one of the rod elements shown in the preceding figures;

FIGURE 4 is a view corresponding to FIGURE 2, but illustrates an alternative embodiment;

FIGURES 5 and 6 are cross-sectional views through the lamp along the reference lines V—V and VI—VI, respectively, of FIGURE 2;

FIGURE 7 is a cross-sectional view through a typical highly-loaded fluorescent lamp provided with a coaxial rod illustrating the character of the discharge that occurs in lamps employing such construction; and

FIGURE 8 is a view, partly in cross-section, of an arrangement for attaching the rod assembly to the inner surface of an uncoated envelope in accordance with the invention.

While the present invention can be advantageously employed in various types of electric discharge devices, it is particularly adapted for use in conjunction with highly-loaded fluorescent lamps and it has, accordingly, been so illustrated and will be so described.

With specific reference to the drawing, in FIGURE 1 there is shown a 100 watt highly-loaded fluorescent lamp 10 that incorporates the rod structure of this invention. The lamp is approximately 4 foot long and consists of the usual tubular light-transmitting envelope 12 having a mount 14 and an associated electrode 16 sealed into each of its ends. The envelope contains the usual charge of mercury and a suitable ionizable starting gas such as argon, neon, krypton, etc., or mixtures thereof. In this particular example the envelope is of the so-called "T17" variety and thus has a diameter of 2 1/8". A heat-deflecting disc 15 is attached to each of the electrode mounts to provide a cooling chamber at each end of the lamp which maintains the mercury vapor pressure at the optimum value in the well known manner. A base member 18 is attached to each end of the envelope to facilitate mounting the lamp in its fixture and connecting it to a power supply. The inner surface of the envelope is coated with a suitable UV-responsive phosphor 13 in the customary manner.

The Invention

Suspended within the discharge space between the electrodes 16, in accordance with this invention, are a plurality of elongated vitreous members such as glass rods 20. As shown in FIGURE 1, the rods are preferably mounted in end-to-end relationship with one another and extend along the envelope axis for substantially the entire length of the discharge space so as to effect the optimum reduction in the diffusion length of the discharge and increase in lamp loading, in accordance with the teachings of the aforementioned copending U.S. application Serial No.

112,071, of D. A. Larson et al. This invention is directed to the problem of mounting the rod in the desired coaxially extending relationship with the envelope without mechanically weakening the lamp and thus constitutes an improvement over the basic invention disclosed and claimed in the aforesaid copending application of Larson et al.

As shown in FIGURE 1, and more particularly in FIGURES 2, 3, 5 and 6, each of the glass rods 20 are provided at one end with a transversely extending leg portion or strut 22 that is formed by bending the end of the rod through substantially a right angle. The rods are mounted in the desired longitudinally extending position within the envelope by sealing the ends of the struts 22 directly to the inner walls of the envelope 12 before the latter is coated with phosphor. The rods 20 are preferably of circular cross-section and oriented so that the strut portions 22 of adjacent rods lie next to one another, as shown in FIGURES 1 and 2, to permit two rods to be attached to the envelope by means of a single sealing operation. The rods are also of substantially uniform diameter throughout their length.

The length of the struts 22 is approximately equal to half the diameter of the envelope 12 so that the rods 20 are in substantially coaxial alignment with the envelope axis and with the discharge space when they are sealed to the envelope wall.

The length of the rods 20 is such that they are sufficiently rigid to withstand the mechanical impacts normally encountered during handling and shipment, even though they are anchored at only one end.

As will be noted in FIGURE 3, each of the struts 22 is joined to the straight body portion of the respective rods 20 by a bent portion 23 that has a relatively large radius of curvature R. Experience has shown that this configuration spreads any stress developed in the bend upon impact over a wide area and prevents the rods from breaking at this point. This rod configuration is, accordingly, preferred. Comparative drop tests have shown that the radius of curvature R should be about three times and at least twice the rod diameter in order to avoid breakage at the bend under normal shipping conditions.

Assembly

A preferred method for sealing the glass rods 20 to the envelope 12 is shown in FIGURE 8. As there shown, the uncoated envelope 12 is first placed on a pair of rollers 25 and 26. The glass rods are then placed into a slot 28 in an elongated jig 30 and the entire assembly inserted into the envelope. The ends of the jig extend beyond the envelope and are supported by a suitable fixture (not shown) located outside the envelope.

After the jig 30 is oriented so that the ends of the struts 22 practically touch the walls of the envelope 12, as shown in FIGURE 8, the envelope is rotated by means of the rollers through a soft gas flame 27 to preheat the portions of the envelope that are aligned with the struts. The jig 30 and its supporting fixture, however, remain stationary.

When the aforesaid envelope portions have been heated to the proper temperature, the rotation of the envelope is stopped. A gas burner 32 located outside the envelope is then positioned over the envelope and the portion of the envelope wall that overlies the ends of the struts is heated by means of a concentrated sealing fire 34. As the heated portion of the envelope becomes soft, it sinks inwardly toward the ends of the struts (which are also heated and softened) and subsequently comes into contact therewith to form a mass of molten glass thus sealing the members together.

Due to the slight deformation of the envelope wall produced by the sealing operation, a plurality of shallow indentations 33 are formed in the outer surface of the envelope 12 at the points where the glass struts are attached, as shown in FIGURES 1, 2, 5 and 6.

5 In order to form a strong seal the rods 20 are preferably fabricated from the same type of glass as the envelope and, in the usual case, this will be lime glass. However, different glasses can be used providing the expansion coefficients of the envelope and rods are matched so as to prevent the introduction of strains which would weaken the seal and cause it to fail.

10 After the sealing operation has been completed, a suitable phosphor coating mixture is flushed through the envelope and the latter is processed into a finished lamp in the usual manner. The rods 20 and struts 22 are thus coated with a layer 21 of UV-responsive phosphor along with the envelope 12 during the regular sequence of operations normally followed in fabricating the lamp.

Background

20 FIGURE 7 illustrates the effect which an axially extending member such as a rod C has on the discharge of a typical low-pressure discharge device such as a fluorescent lamp L. The rod and the inner surface of the envelope E are coated with phosphor P, as in the case of the preferred lamp embodiment described above. As shown, the presence of the rod at the axis of the envelope shifts the region of maximum arc intensity and electron density from the center of the discharge space outwardly toward the walls of the envelope. The arc A is accordingly annular in cross-section and is coaxial with and located approximately midway between the rod and the envelope walls. Since the rod, and thus the recombination surface, are located at the envelope axis where the electron density and arc intensity are normally at a maximum, a maximum decrease in the diffusion length of the discharge is achieved with this arrangement.

25 A detailed account of how the presence of the rod enhances the light output of the lamp and the reasons why it is important to correlate the diameter of the rod with that of the envelope is set forth in the aforementioned copending application of D. A. Larson et al.

Specific Example

30 The following specific example will illustrate the relative sizes of the components required to obtain the structural advantages afforded by the invention in a particular lamp. In the case of the 100 watt 4 foot T17 lamp such as that shown in FIGURE 1, satisfactory strength and efficiency were obtained by employing six rods each having an overall length of about 6½ inches. The ends of adjacent rods were spaced about ¼ to ½ of an inch apart so that the total distance spanned by the rods was approximately 3½ feet, or substantially the entire length of the discharge space between the electrodes. The rod diameter was approximately ¼" and the radius of curvature of the bent portions was about ¾".

Alternative Embodiment

35 As shown in FIGURE 4, a single rod 24 of equivalent length can also be used instead of a plurality of short rods 20 as in the preferred embodiment above described. In this case, the rod 24 would be supported in substantially coaxial relationship with the envelope 12a by means of a plurality of spaced vitreous struts 26, such as short lengths of glass cane, that are sealed to the rod as well as to the inner surface of the envelope. In order to avoid the possibility of breakage due to excessive vibration, a sufficient number of struts are used to keep the rod relatively rigid. For example, five struts spaced about 6½ inches apart and inwardly from the ends of the rod are used in the case of a four foot lamp to maintain substantially the same unsupported span length as in the preferred embodiment.

40 The struts 26 are sealed to the inner surface of the envelope 12a in the same fashion as described above so that shallow indentations 33a will again be formed in the outer surface of the envelope, as shown in FIGURE 4. The inner surface of the envelope is coated with phosphor 13a and the struts and rods are also coated with phosphor 21a

so that the alternative lamp embodiment 10a is identical from a functional standpoint with the preferred lamp embodiment described previously.

It will be appreciated from the foregoing that the objects of the invention have been attained by providing an arrangement for conveniently mounting an elongated fragile rod in a predetermined position within a fluorescent lamp or the like without materially obstructing the discharge space or weakening the lamp. Moreover, the configuration of the short rods employed in accordance with the preferred embodiment is such that the rods can be easily produced on a mass production basis with a minimum of cutting and shaping operations.

While several embodiments have been illustrated and described in detail, various structural and procedural modifications can be made without departing from the spirit and scope of this invention. For example, both ends of the short rods can be bent to provide strut segments, or a single strut located intermediate the ends rather than at one end of the rods can be used.

I claim:

1. In an electric discharge device having an elongated envelope that contains a pair of spaced electrodes located proximate the ends of said envelope, the combination of a substantially rigid rod-like member located in and extending longitudinally of said envelope and the discharge space between said electrodes, and means suspending said member in a predetermined region of the discharge space remote from the envelope walls and remote from said pair of electrodes comprising at least one strut that extends transversely of the discharge space and is joined to and integral with said rod-like member and the inner surface of said envelope.

2. The combination in an electric discharge device of a rod-like member and a support strut as set forth in claim 1 wherein said strut comprises a vitreous element that is sealed to the inner surface of said envelope.

3. In a UV-generating device having a vitreous envelope of tubular configuration that contains an ionizable medium and a pair of electrodes located proximate its ends, the combination of a substantially straight vitreous rod extending longitudinally of said envelope and the discharge space between said electrodes, and a vitreous strut sealed to the inner surface of said envelope and integrally joined to said rod, said strut extending transversely of the discharge space and being of such length that said rod is spaced from the envelope walls and suspended solely by means of said strut in a predetermined region of the discharge space between said pairs of electrodes.

4. The combination in a UV-generating device of a conjoined vitreous rod and support strut as set forth in claim 3 wherein said strut is of such length that the rod is supported in substantially coaxial relationship with said envelope.

5. In a fluorescent lamp having a tubular glass envelope and a pair of electrodes sealed into the ends of said envelope, the combination of a glass rod extending longitudinally of said envelope and the discharge space between said electrodes, and a transversely extending glass strut sealed to said rod and the inner surface of said envelope and suspending said rod at substantially the

axis of said envelope and at a location therein remote from and between said pair of electrodes.

6. The combination in a fluorescent lamp of a glass rod and support strut as set forth in claim 5 wherein said strut comprises a bent end portion of said rod, and said strut and rod are both coated with UV-responsive phosphor.

7. A fluorescent lamp adapted for operation at a loading of about 25 watts per foot comprising, a tubular envelope of vitreous material, an electrode disposed at each end of said envelope, a plurality of relatively short vitreous rods arranged in end-to-end relationship within said envelope and extending longitudinally thereof and the discharge space between said electrodes, and a transverse strut integrally joined to each of said rods and sealed to the inner surface of said envelope, said struts being of such length and so disposed that said rods are substantially aligned with one another and with the axis of said envelope and are suspended within the discharge space at a location remote from both of said electrodes.

8. A fluorescent lamp as set forth in claim 7 wherein each of said rods are of circular cross-section and substantially uniform diameter throughout their length, and said struts comprise bent end segments of the respective rods.

9. A fluorescent lamp as set forth in claim 8 wherein said struts are joined to the respective rods by a bend having a radius of curvature greater than about twice the rod diameter.

10. A fluorescent lamp comprising, a tubular glass envelope, an electrode sealed within each end of said envelope, a substantially straight and rigid rod-like member within said envelope extending longitudinally thereof and along a major portion of the discharge space between said electrodes, and a plurality of transversely extending struts of vitreous material sealed to the inner surface of said envelope at intervals along the discharge path and suspending said rod-like member in substantially coaxial relationship with said envelope at a location therein remote from and between said electrodes.

11. A fluorescent lamp having an overall length of approximately four feet comprising, a tubular glass envelope approximately $2\frac{1}{4}$ inches in diameter, a thermionic electrode sealed into each end of said envelope, six glass rods disposed in end-to-end relationship within said envelope and extending longitudinally of the discharge space between said electrodes, each of said rods having an overall length of approximately $6\frac{1}{2}$ inches and the ends of adjacent rods being spaced a predetermined distance apart, and a corresponding number of transverse glass struts joined to the respective rods and to the inner surface of said envelope, the length of said struts being approximately equal to half the diameter of said envelope so that said rods are substantially aligned with one another and are suspended solely by means of said struts in substantially coaxial relationship with said envelope.

12. A fluorescent lamp having an overall length of approximately four feet comprising, a tubular glass envelope approximately $2\frac{1}{4}$ inches in diameter, a thermionic electrode sealed into each end of said envelope, six glass rods disposed in end-to-end relationship within said envelope and extending longitudinally of the discharge space between said electrodes, each of said rods having an overall length of approximately $6\frac{1}{2}$ inches and the ends of adjacent rods being spaced a predetermined distance apart, and a corresponding number of transverse glass struts joined to the respective rods and to the inner surface of said envelope, the length of said struts being approximately equal to half the diameter of said envelope so that said rods are substantially aligned with one another and are suspended solely by means of said struts in substantially coaxial relationship with said envelope.
